COMBINED GRAB BAR AND RECESSED WALL FIXTURE FOR SOAP OR SIMILAR ARTICLE

French Eugene Smith, Akron, Ohio, assignor to Miraplas
Tile Company, Columbus, Ohio, a corporation of Ohio

Application April 7, 1958, Serial No. 50,355

Term of patent 3½ years

(Cl. D4—3)

Figure 1 is a perspective view of a combined grab bar and recessed wall fixture for soap or similar article, showing my new design, the soap dish shown in broken lines being for illustrative purposes only.

I claim:

The ornamental design for a combined grab bar and recessed wall fixture for soap or similar article, substantially as shown and described.
